UNITED STATES PATENT OFFICE.

HARRY WARD, OF NEWARK, NEW JERSEY, ASSIGNOR TO OSCAR E. A. WIESSNER, OF BROOKLYN, NEW YORK.

DESIGN FOR A HEADBOARD OR FOOTBOARD FOR BEDSTEADS.

SPECIFICATION forming part of Design No. 28,368, dated March 8, 1898.

Application filed September 3, 1897. Serial No. 650,539. Term of patent 3½ years.

To all whom it may concern:

Be it known that I, HARRY WARD, a subject of the Queen of Great Britain, and a resident of Newark, in the county of Essex and State of New Jersey, have invented a certain new and useful Design for a Headboard or Footboard for Bedsteads, of which the following is a specification.

This invention relates to a design for a headboard or footboard of a metallic bedstead and is illustrated in the accompanying drawing, which forms a part of this specification.

The essential features of this design embrace the parts of the headboard or footboard as shown and described with the exception of the mounts and finials at the upper ends of the side posts.

In the drawing, A refers to the posts, which are terminated by beaded mounts B, which in turn are capped by the finials C. At the middle of these posts and at their lower ends are scalloped and scroll-bordered plates D. A rail E extends from the mount B on one post to the mount B on the other and is arched or bowed at its middle. At a slight distance below the rail E is another horizontal rail F, extending straight across from one post to the other. Between the rails E and F, at either side of the design, are three double truncated conical spindles G, and on the opposite side of said rails in alignment with these spindles are balls or spheres H.

Extending from one post to the other near the lower ends thereof is a horizontal rail I. Three vertical rods, as J K, extend from the middle portion of the rail F to the middle portion of the rail I, and parallel thereto at either side of the design near the posts A are vertical rods L, extending from the rail I to the

rail F. Near the middle of the rods L and J 40 there is a short horizontal rail M, extending from one to the other, and from the middle of each of these rails there extends a short vertical rod N, which meets at its lower end the rail I. 45

Under the arched portion of the rail E and extending to the rail F is a conventional figure O, having a fan-like top and legs of scalloped scrolls. This same figure O is repeated in the rectangles formed by the rails M F and 50 rods J L at either side of the design. At opposite sides of the rails with which these conventional figures meet are balls or spheres P.

At the junction of the rails F and I with the posts A are located scalloped and scroll-bordered plates D', similar to those at the middle of said posts. 55

At the junction between the horizontal rails and the vertical rods are scalloped plates Q, terminating on one side in a projection resembling in form an arrow-head. 6c

Upon the vertical rod K, near its ends, are scalloped plates R.

In the centers of plates D, D', Q, and R there are scalloped rosettes having radial lines 65 extending from a circle in the center thereof to the intersection of the scallops.

What I claim as my invention is—

The design for a headboard or footboard of a bedstead, substantially as herein shown and 70 described.

Signed at New York, in the county of New York and State of New York, this 27th day of August, A. D. 1897.

HARRY WARD.
